CLAIM

The ornamental design for portion of a shoe outsole, as shown and described.

DESCRIPTION

FIG. 1 is a perspective view of a portion of a shoe outsole showing my new design;

FIG. 2 is a bottom plan view of the portion of a shoe outsole shown in FIG. 1;

FIG. 3 is an enlarged profile view of the portion of a shoe outsole taken along line 3—3 of FIG. 2;

FIG. 4 is an enlarged profile view of the portion of a shoe outsole taken along line 4—4 of FIG. 2;

FIG. 5 is an enlarged profile view of the portion of a shoe outsole taken along line 5—5 of FIG. 2; and,

FIG. 6 is an enlarged profile view of the portion of a shoe outsole taken along line 6—6 of FIG. 2.

The broken line showing of the remainder of the shoe is for illustration purposes only and forms no part of the claimed design.
